INSTRUMENT FOR CLEANING HYPODERMIC SYRINGES AND THE LIKE
 John Robert Lend, 5247 W. North Ave., Chicago, Ill.
 Filed Mar. 29, 1962, Ser. No. 183,576
 7 Claims. (Cl. 15—118)

This invention relates to an instrument or tool devised for cleaning hypodermic syringes, test tubes, and the like.

More specifically, the instrument comprises a tool having the facility of cleaning relatively long narrow diameter containers or receptacles with particular access into corner areas that are normally hard to reach and clean.

One of the objects of this invention is to provide an instrument having configurations thereon that lend themselves specifically to certain hard to get at cleaning areas of syringe barrels and to tubular or long and narrow receptacles to efficiently and completely remove all debris and sediment therefrom to place such receptacles in condition for further use or for additional processing by sterilization, etc.

Another object is to provide a cleaning instrument having configuration areas or surfaces oriented in such a way as to accept various selected forms of cotton on portions of the instrument, which portions have the facility to establish more intimate and beneficial cleaning contact with the interior of a restricted vessel or receptacle being cleaned.

A further object is to provide a tool or instrument having a flexible intermediate portion or shank wherewith to flex the instrument by reaction of the shank on the rim of the receptacle or syringe barrel being cleaned, causing the cleaning end thereof to assume an extended cleaning contact with the side wall of the receptacle. The instrument has a blunt end portion on the wall orientation contacting portion of the shank end, and by using a swirling motion on the extended tool and beyond the receptacle, the cleaning end follows a rotary path within the receptacle or syringe to eliminate foreign sediment and debris from the bottom wall of the barrel and from the adjacent vertical or circumferential wall of the article being cleaned.

And as a further object, the instrument is made of plastic material such as nylon or the like having limited flexibility with good recovery properties after distortion to resume its original shape and to hold it after flexing during use to carry out the cleaning function.

Other objects and advantages shall hereinafter appear in or become apparent from the following detailed description of the cleaning instrument of the present invention having reference to the accompanying drawing forming a part of this specification.

In the drawing:

FIG. 1 is an enlarged side elevational view of the cleaning instrument of this invention;

FIG. 2 illustrates a barrel of a hypodermic syringe in section and shows how the instrument is used in a swirling motion, with cotton attached to its end, to obtain the efficient and effective cleaning action made possible with this tool.

FIG. 3 is a vertical cross sectional view through the syringe barrel substantially as taken along the plane of the line 3—3 in FIG. 2 to further illustrate the cleaning action with this tool or instrument;

FIG. 4 is an end elevational view of the top of the instrument of FIG. 1 to show the configuration thereof;

FIG. 5 is a cross sectional view of the instrument shank as it generally appears in the plane of the line 5—5 in FIG. 1; and

2

FIG. 6 is a fragmentary side elevational view of the lower end of the instrument showing a modified tip.

The instrument is best illustrated in FIG. 1 and comprises a head 1, a shank 2 and a tip 3. The shank 2 is slightly tapered from the head end to the tip end for greater flexibility of the lower portion of the instrument. As seen in FIGS. 1 and 5, the shank is made to include longitudinal ridges 4 or similar configurations for better pick up and for grasping the instrument when applying cotton to the ends thereof prior to use and to aid removal of the cotton from the head or tip end as the case may be.

The tool or instrument is preferably made from a flexible material and may be completely so made although the flexibility may be confined to the shank portion only if desired for obtaining the action needed to clean receptacles. While other kinds of material having a flexible character can be used to make this instrument, a material such as nylon provides the necessary flexibility and memory characteristics particularly well adapted to an instrument of this nature. The instrument must have limited flexibility or resilience, but it must also have the property of resuming its original undistorted shape or form.

The head 1 is multi-surface or plane sided in cross sectional shape as seen from FIGS. 1 and 4 to afford a hand hold or finger grip means to bodily rotate the rest of the instrument during cleaning inducing its flexing and propelling the tip 3 bodily about the bottom of a receptacle such as the syringe 5.

The head comprises a terminal end 6 having pyramidal projections 7 thereacross formed in a common plane and notches 8 are provided on one or more of the vertical edges thereon as seen in FIGS. 1 and 4. A rectangular slot 9 is cut out of the head to provide a wrench facility to aid in removing a syringe needle such as 10 by means of its nut end 11 seen in FIG. 2.

It is the head 1 that provides a means for accepting a cotton piece for use in cleaning large receptacles such as test tubes and the like. Cotton is wound around the head to a suitable thickness, by first applying a portion thereof against the pyramidal end 6 to lay across the crevices of the associated pyramidal elements 7, and then bringing the cotton about the periphery of the head to engage into the notches 8 and slot 9 while wrapping the cotton about the multi-surfaced sides of the head.

In cleaning with head 1, the instrument is normally axially rotated with the shank and or with the oblong head. The head with its four flat angularly related sides and with the restraining cavities acts to prevent independent rotation or loosening of the cotton. Furthermore, the cotton on the end of the head, which does a great deal of the cleaning, is held against rotation by the elevated elements or pyramidal units 7 to insure good effective cleaning action. The apexes of the pyramidal elements 7 also induce spaced pressure points in the cotton to act through the cotton to help clean and clear the surface being worked upon.

The tip 3 of the instrument is disposed at the lower end of the shank 2 and ahead of an annular recess 12 and provides a tapered unit generally defined by a conical outer wall surface 13 converging toward a stub end 14 formed substantially square with the axis of the instrument. Circumferential ridges 15 or similar roughened surface configurations surround the tapered tip walls and vertical smooth areas 16 or separations divide the roughened areas into groups. The tip taper bears a predetermined conical angular relationship with respect to the axis of the instrument to obtain considerable intimate cleaning contact with extended wall portions of a syringe, one example thereof being best illustrated in FIG. 2.

By segregating the ridges 15 into groups along the length of the tip circumference, cotton strip or wad portions can be wound upon the tip from either direction peripherally and the cotton will be caught by the sharper edge portions at one side of the smooth areas 16 by turning the instrument in one direction; while the reverse will be true when applying cotton and rotating the shank in the opposite direction.

Cotton will normally be placed over the stub end 14 of tip 3 and then guided upwardly and about the tip by rotating the shank. From experience, just enough cotton may be used from habit to cover the end and tip over the length of the latter. If too much cotton is used or applied, a certain amount of the excess will be entwined about and within the annular recess 12.

The recess 12 is further provided as a means to allow greater flexibility of action of the tip 3 relative to the end of shank 2. A certain amount of adjustment of the axis of the tip in relation to the adjacent axis of the shank is hereby possible to thereby let the tip and the cotton thereon assume a better cleaning position against the surface being cleaned while under the radial pressure of the bowed shank on the tip. The circular action of the shank will further react through the recess 12 to allow the tip to also adjust angularly somewhat within the circular path of travel about the wall area being cleaned to tend to create a drag effect under operation.

As shown in FIGS. 2 and 3, absorbent cotton such as 17 has been applied to the tip 3 of the shank 2 and the latter is shown inserted into the barrel 18 of the syringe 5. The most troublesome spot or area to clean is the shoulder portion 20 of the barrel 18. By bowing the flexible shank within the barrel 18 and using the outer barrel mouth corner 21 as a reactionary or fulcrum point, shank 2 causes the tip 3 to be urged toward the opposite wall 22 of the barrel, thus causing the radially outer wall 13a of the tip to substantially lie in parallel position adjacent to a considerable length of the wall surface 23 of the syringe. By a downwardly urged seating action of the shank toward shoulder 20 compounded with the lateral reactionary manipulation of the shank over a corner 21, the cotton will tightly hug the wall 13a and also seat tightly against shoulder 20. The instrument will function in this manner in any radial plane.

The cleaning function is carried out by circumferentially and slidably moving the instrument about the mouth of the syringe barrel using the open barrel end as a fulcrum for the intermediate portion of the shank 2. By holding the instrument bowed radially outwardly while maintaining the same bodily actuation thereof without rotation of the shank on its axis, which function is well made possible by holding the head 1 tightly with the fingers, the cleaning tip 3 imitates the same circular motion within the barrel base describing an arc limited by the barrel walls with the stub end of the tip 3 riding against the bottom shoulder of the barrel. It is the tip pressure against the walls that is effective to align the tip held cleaning material with the wall and the stub end forces the cleaning material down on the barrel shoulder, and by reason of this action, the cleaning action is efficient and effectively performed in the most difficult barrel cleaning area of the syringe.

Further rotary and/or endwise movement of the instrument with deflected shank acts to clean the balance of the tube or barrel all prior to certain reuses or to sterilization as the case may be.

It is to be understood that the instrument when equipped with cotton, at one or the other ends thereof, is dipped into a cleaning substance such as a commercial detergent or in any other suitable cleaning mixture or compound adapted for such purposes.

The instrument, therefore, is one which by its flexibility and shape performs a cleaning operation in a syringe barrel, for example, with controlled and predetermined motions under resilience, to induce radially outwardly

directed pressure on cotton or the like that is releasably connected with the instrument to carry out the cleansing operation by circular manipulation of the instrument.

FIG. 6 shows a modified instrument tip 25 is also tapered and generally smooth surfaced over its length. A spiral groove 26 encircles the smooth tip in screw fashion providing a continuous surface thread that ends at the blunt conical terminal end 27 of the tip. The point 28 of the blunt end 27 is to provide a concentrated pressure point in the cotton directed into the corner portion of the syringe barrel.

Cotton may be rolled upon tip 25 from either direction since it will be held in place by the edge limits of the groove. Removal of the cotton is facilitated by turning the shank 2 and exerting an endwise pull on the cotton toward point 27. The cotton will be easily released with this action and the tip will be ready to receive other cotton.

Both of the described tips 3 and 25 also serve as convenient means for quickly removing cotton and the like from bottles and jars, or from various receptacles.

While the head 1 may also be used to remove cotton or other materials from larger receptacles, the end of the head can be employed as a tamper or material crusher to break up pills or coarse chemicals as the case may be.

The foregoing description relates to certain forms of the invention, but the invention need not necessarily be limited thereto. Certain changes in the structure may be made without departure from the fundamental concept disclosed. All modifications shall, however, be governed by the breadth and scope of the language contained in the appended claimed subject matter directed to the cleaning instrument of the present invention.

What I claim is:

1. An instrument for cleaning the barrels of tubular devices comprising a flexible elongated unitary tool partially insertable into the barrel of a device with the rest thereof extending outwardly beyond the mouth of the barrel, cleaning members connected in line with the opposite ends of said tool, said cleaning members being provided with surface irregularities to accept and to retain cleaning material thereon, one of said cleaning members being polygonal in shape to provide finger grip areas thereon whereby to permit operative flexing of said tool without rotation and to impart bodily circular cleaning motion to the other of said members within the barrel of a tubular device, the other of said cleaning members being provided with a tapered surface contour converging toward its terminal end and away from the tool proper, said tapered portion of said member providing orientation means for the cleaning material to align said material generally with the wall surface being cleaned under the flexing bowed manipulation of the tool about the mouth of the barrel by the finger manipulation of the polygonally shaped cleaning member.

2. An instrument for cleaning the barrels of tubular devices comprising a flexible elongated unitary tool partially insertable into the barrel of a device with the rest thereof extending outwardly beyond the mouth of the barrel, cleaning members connected in line with the opposite ends of said tool, said cleaning members being provided with surface irregularities to accept and to retain cleaning material thereon, one of said cleaning members being polygonal in shape to provide finger grip areas thereon whereby to permit operative flexing of said tool without rotation and to impart bodily circular cleaning motion to the other of said members within the barrel of a tubular device, said other of said cleaning members being provided with a stub terminal end disposed across the tip portion thereof to endwise engage and to seat upon the barrel bottom to urge the cleaning material against shouldered areas in the barrel portion of said tubular devices.

3. An instrument for cleaning the barrels of tubular devices comprising a flexible elongated unitary tool par-

tially insertable into the barrel of a device with the rest thereof extending outwardly beyond the mouth of the barrel, cleaning members connected in line with the opposite ends of said tool, said cleaning members being provided with surface irregularities to accept and to retain cleaning material thereon, one of said cleaning members being polygonal in shape to provide finger grip areas thereon whereby to permit operative flexing of said tool without rotation and to impart bodily circular cleaning motion to the other of said members within the barrel of a tubular device, one of said cleaning members including a cleaning surface portion thereon disposed transversely to the axes of said tool, said surface portion of said member being provided with pyramidal projections thereon to accept and retain cleaning material over the end of said member and between said pyramidal projections to thus establish multiple pressure points by reason of the projections of said member under said cleaning material and to counteract rotation of the material in the plane of said cleaning surface portion of said member.

4. An instrument for cleaning barrels of syringes or the like comprising an elongated substantially smooth surfaced shank member for rotary hand manipulation made of material having limited resiliency with a reformation factor such as nylon, an outwardly converging tapered cleaning tip formed contiguous with said shank member and having a smooth exterior contour surface provided with circumferentially arranged ridges thereon to accept and firmly hold cleaning cotton about and along said smooth surface thereof and against rotation on the tapered tip, and a single annular recess on said instrument disposed between said shank and said cleaning tip to allow more liberal flexing of said tapered cleaning tip with respect to the shank to align the cotton covered surface portion of said tip with respect to the longitudinal wall portion of a syringe barrel that is contacted by said tip and cotton under the rotary hand manipulation of said shank.

5. An instrument for cleaning elongated small diameter receptacle barrels comprising an elongated shank to extend into a barrel and to project outwardly beyond the mouth of such barrel, said shank having a rounded exterior contour to freely move about the barrel mouth during the cleaning operation, a head on the outwardly projecting end of said shank including flat surface areas thereon disposed axially with respect to the shank to establish finger grip means arranged beyond the adjacent end of the shank, a cotton accommodating head forming an elongated tip on the barrel confined end of said shank and having a conical shape tapering away from the shank for backing said cotton to engage in elongated line contact while sweeping the periphery of the barrel interior under the manipulation of the shank through said flattened finger grip means, said shank and its connected heads being made of flexible material to permit bowing of the

shank and the relative axial displacement of the heads with respect to each other, said instrument further including an annular recess arranged thereabout and interposed between the shank and the cotton accommodating head

- 5 to establish a reduced diameter portion to enhance the angular tilting of the cotton accommodating head with respect to said shank for the orientation of said latter head and the cotton carried thereon for elongated full length barrel surface contact during the cleaning operation.
- 10 6. An instrument for cleaning the barrels of tubular devices comprising a flexible elongated unitary tool partially insertable into the barrel of a device with the rest thereof extending outwardly beyond the mouth of the barrel, cleaning members connected in line with the opposite ends of said tool, said cleaning members being provided with surface irregularities to accept and to retain cleaning material thereon, one of said cleaning members being polygonal in shape to provide finger grip areas
- 15 20 thereon whereby to permit operative flexing of said tool without rotation and to impart bodily circular cleaning motion to the other of said members within the barrel of a tubular device, the other of said cleaning members being provided with a tapered surface contour converging
- 25 30 35 toward its terminal end and away from the tool proper, said tapered portion of said member providing orientation means for the cleaning material to align said material generally with the wall surface being cleaned under the flexing bowed manipulation of the tool about the mouth of the barrel by the finger manipulation of the polygonally shaped cleaning member, said surface irregularity on said other of said cleaning members comprising a continuous spiral groove extending along the tapered surface contour of said member and exiting outwardly at the free terminal end of the tapered member to permit rotary application of cleaning cotton upon the tapered surface contour of the tapered member and the quick removal of such cotton in screw fashion axially off of the terminal end of said tapered member.

- 40 7. In an instrument of the character set forth and defined in claim 6, with the addition of a blunt conical point on the terminal end of said tapered member and at the exit portion of said spiral groove.
